UNITED STATES PATENT OFFICE.

JOHN GILSON, OF PORT WASHINGTON, WISCONSIN.

DESIGN FOR A BRACE-PIECE FOR TABLE-LEGS.

SPECIFICATION forming part of Design No. 32,625, dated May 1, 1900.

Application filed April 2, 1900. Serial No. 11,263. Term of patent 14 years.

To all whom it may concern:

Be it known that I, JOHN GILSON, a citizen of the United States, residing at Port Washington, in the county of Ozaukee and State of Wisconsin, have invented and produced a new and original Design for a Brace-Piece for Table-Legs; and I do hereby declare the following to be a full, clear, and exact description of the same, reference being had to the accompanying drawings, forming a part thereof.

In the said drawings, Figure 1 is a plan view, Fig. 2 a side elevation, and Fig. 3 a detail sectional view, taken on the line 3 3 of Fig. 1, of a brace-piece for table-legs embodying my new design.

My design relates to the new and original shape or configuration of the article.

The leading or essential feature consists in the unitary design for a brace-piece for table-legs made the subject of illustration, comprising the shape of the skeleton top, formed of three concavely-curved portions A A A, interrupted and united by the three short straight portions B B B, all on the same horizontal plane. From each one of the said short portions B there depends an outwardly-flaring flange C, formed on an outer straight oblique line from top to bottom, there being parallel-walled perforations D through the faces of said flanges C. Between the front faces of each two adjacent flanges the brace-piece is formed on concavely - rounded lines corresponding to the curve of the portions A of the skeleton top and coinciding at the top with the outer curved line of said portions A, but

slightly flaring outwardly in a downward direction, so that the lower end of each flange-face is wider than the upper end thereof, and these portions E of the brace-piece between the flanges are of least depth at the center, 40 where they are formed on a semicircular lower line, as shown between the points a a in Fig. 2, on each side of which the lower edge of each part E is formed on short straight horizontal lines, as indicated between the points 45 a b a b, and thence on rounded convex lines down to the bottom of the flanges C C, as indicated between the points b c b c, and this just-described outline c b a a b c is substantially followed by an upper border-line, forming an ornamental edging F to the part E, which projects outwardly to a slight distance beyond the outer surface of the said part E.

Minor features of said design comprise a rounded boss G at the center of the skeleton 55 top, connected by arms H H H to the centers of the inner edges of the portions B B B of said skeleton top.

Having thus described my invention, what I claim as new, and desire to secure by Letters 60 Patent, is—

The design for a brace-piece for table-legs, substantially as herein shown and described.

In testimony whereof I affix my signature in presence of two witnesses.

JOHN GILSON.

Witnesses:

EDWARD BARELMAN,
C. A. SEIFERT.
